UNITED STATES PATENT OFFICE

2,478,646

SPICE MILL

John M. Thompson, Grosse Pointe, Mich.

Application May 16, 1945, Serial No. 594,017

2 Claims. (Cl. 241—260)

1

This invention relates to a grinding mill and more particularly to a household device suitable for the processing of small amounts of spices without the subsequent loss of flavor.

Heretofore, the smaller household or table units used for the disintegration of the various spices have been miniature reproductions of the larger production models. These have been designed to either operate continuously or until all of the spices in the mill have been processed. Thus the lack of linear flow of the material through the grinder area and the lack of control in the rate of feed to the grinding zone which results in a large percentage of partially ground material being thrown back into the feed section has not been considered detrimental. However, the small household units must be designed to process only the small amount of spices to be immediately used, and of necessity must function as a storage unit as well as a grinder, whereon the large percentage of partially ground material thrown back would then be exposed to the atmosphere for days or perhaps weeks. It is well known that the outer shell of these kernels serves as a protective covering which prevents the rapid evaporation of the oils contained within, and once the shell is broken the oils are rapidly dissipated and the subsequent materials ground therefrom would have considerably less flavor. In addition, the operation of the former grinder has required more effort because of the lack of control in the rate of feed into the grinding zone.

An object of the invention is the production of a spice grinder adapted to the intermittent usage of a household table model such that it operates efficiently as a grinder and as a storage unit.

A further object of this invention is the production of a grinder adaptable to household usage which operates easily and quietly, and may be adjusted to produce variable sized granules.

A further object of this invention is the production of a grinding mill which controls the amount of feed to that which will be subsequently ground and used and is so constructed that practically none of the ground material rises from the grinding zone into the storage area.

A further object of this invention is the production of a spice grinding mill in which the grinding elements may be made by simple casting processes and the wear of the grinding elements is substantially eliminated. Other objects will hereinafter appear, and for purposes of illustration but not of limitation, an embodiment of

2

this invention is shown in the accompanying drawings, in which

Figure 1 is a side view of the grinder unit showing the turning unit in full view and the retainer ring, grinding ring and retainer bar in section;

Figure 2 is a top view of the grinder ring only showing the equally spaced grooves;

Figure 3 is a view through the line 3—3 of Figure 1; and

Figure 4 is a bottom view of the grinder unit showing specifically the triangular lug and the retainer bar as assembled with the grinding ring and turning unit. The retainer ring is not shown in this view.

10 The grinding ring 12 extends upwardly from the shoulder 11, the outside part 15 having the form of a straight cylinder and the inside section hollowed out to appear as the frustum of a cone. The opening 16 at the bottom of the grinding ring is relatively narrow and the sides rise at an angle A of about 25° from the vertical, indicated by dot-dash line V. Equally-spaced grooves 17 in the inside surface of the grinding ring each are defined by a flat, substantially triangular surface 18 lying in the radial plane of the cone of which surface 18 is a frustum, and an adjacent surface 20 formed substantially as a generatrix of a line swing in an arc B about point P. Thus the junctions of surfaces 18 with surface 21 form sharp cutting edges 18a, the form of the grooves provides free downward flow of the material while avoiding pockets for entrapment of material, and the unground sections 22 of surface 21 between and below the grooves serve as a bearing on which the turning unit 23 may ride, thus reducing wear on cutting edges 18a.

15 The illustrated embodiment of the invention comprises a retainer ring 10 which is recessed at its lower inside edge such that the extended shoulder 11 of the grinding ring 12 may fit therein. Holes 13 are formed in the shoulder 11 and in a corresponding location, taps are machined in retainer ring 10 whereby screws 14 may be used to securely attach the grinding ring 12 to the retainer ring 10.

20 The main body 24 of the turning unit 23 is shaped like a frustum of a cone and is cut or cast such that its outside surfaces 25 are parallel to the inside surfaces 21 of the grinding ring 12 and is of such dimensions that the turning unit 24 fits therein, the bottom and top edges of the turning unit body 24 being substantially flush with the bottom and top edges of the grinding unit 12. Flutes 26 formed in the turning unit are each defined by two surfaces. Surface 27 is

flat and bound by a top edge 27a at its juncture with the flat horizontal top surface 24a of turning unit body 24; the peripheral edge 27b, as seen in elevation, forms an angle as indicated by the dot-dash arc B with the flat horizontal top surface 24a of substantially 55°; the inner edge of surface 27 forms an angle, as indicated by the dot-dash line C, with surface 24a of about 62°. Surfaces 28 are each parallel to diametrical planes of the cone of which the peripheral surfaces 25 of turning unit body 24 form a frustum, each being bound by a top edge 28a at its juncture with top surface 24a of the body 24; peripheral edges 28b forms the juncture of surface 28 and peripheral surface 25 of unit 24, and the inner edge of surface 28, and the inner edge of surface 27 have the common junction 27a, which is filleted so as to avoid the formation of pockets in which material may collect. The depth of the flute is such that the bottom of edge 28b just meets the bottom edge of turning unit 24. The outside surfaces 25 between the flutes serve as a bearing which rides on the surfaces 21 of the grinding unit 12.

The main body 24 of the turning unit 23 is integral with a long spindle 30 which may either be rounded or square. Said spindle 30 may also be a separate unit which may be inserted into a hole or slot drilled into said body 24. A triangularly shaped lug 33 on the lower end 31 of the spindle 30 extends below the body 24 of the turning unit 23 in order that it may operatively engage and turn the multiple prongs 34 of the retainer bar 32. The retainer bar 32 is movable upon the lug toward or away from said grinding ring 12 and turning unit 23 as for example, in response to the adjustment of a nut 35 on the threaded end portions 36 of the spindle 30 and serves to hold the turning unit 23 under tension within the grinding ring 12 as well as wiping the lower edge of the grinding ring. The adjustment of said retainer bar 32 on the lug 33 regulates the tension and the degree to which the turning unit 23 is pulled into the grinding ring 12 and thus regulates the annular space between the turning unit and the grinding unit through which the ground kernels pass, thus controlling the various grades of grind.

In operation the space 35 between the upper portion of the spindle 30 and the retainer ring 10 serves as a storage unit for the whole kernels. As the turning unit 23 rotates, sufficient kernels to fill the large flutes 26 fall therein, and due to the funneling effect of the grooves 17 and the flutes 26, are forced downwardly until they are pressed against the cutting edges and the straight edge 18 where the kernels are broken into finer granules. The downward movement and disintegrating action continues until the material reaches the bottom of the slots at which point they are sufficiently reduced to pass through the annular space between the turning unit 23 and the grinding unit 12, as previously pointed out. The retainer bar 32 does not restrict the passage of processed material, as only the prongs extend to the grinding unit 12. Other whole kernels can not enter the flute 26 until the former material has been practically expelled, thus eliminating the probabilities of a large amount of partially ground spices being left in the unit to dry out before the next operation. Thus only a small amount of material can be contained between the grinding surfaces, and, having once entered between the grinding surfaces, that material is

passed directly through without likelihood of reversion to the storage unit.

It is to be understood that numerous changes in details of construction, arrangement and operation may be effected without departing from the spirit of the invention, especially as defined in the appended claims.

What I claim is:

1. A grinding mill suitable for the reduction of small increments of spices or the like, comprising a retainer ring, the upper portion of which may serve as a container or storage space for the whole kernels, a grinding ring on the lower portion of the retainer ring, a frustum shaped opening through the grinding ring, spaced grooves in the inner surface of the grinding ring having one side straight making a sharp angle with the inside surface of the grinding ring with the other sides rounded and at an angle so that the grooves taper downwardly and terminate near the bottom edge of the grinding ring, a bearing surface between said grooves, a frustum shaped body fitting exactly into said frustum shaped opening in the grinding ring, flutes spaced in said body, the cone side of each flute being at an angle with the horizontal and the vertical and forming a downwardly and rearwardly inclined surface with the other side substantially parallel to the center line of the unit, said flutes extending downwardly to the edge of the frustum, and a spindle extending through the body and having a driving connection therewith.
2. A grinding mill for spices or the like, comprising a frusto-conic rotary member, a stationary member having a frusto-conical aperture adapted to receive said rotary member in a manner disposing the end of smaller diameter in the base thereof, one or more cooperating vertically disposed cavities in the adjacent peripheral walls respectively of the rotary and stationary members adapted concomitantly to effect grinding and to direct downward flow to the spice kernels in response to turning movement of said rotary member, the adjacent peripheral walls intermediate said grooves operating as bearing surfaces, a spindle having a driving connection with said rotary member, a retainer member operatively engaging a depending portion of said spindle and abutting the base of said stationary member, and means for adjusting said retainer member relative to said rotary member.
